CHECKER ASSEMBLY

Owen R. Rice, Chicago, Ill., assignor to Freyn Engineering Company, Chicago, Ill., a corporation of Maine

Application January 17, 1946, Serial No. 641,730

8 Claims. (Cl. 263—51)

1

The present invention relates to improvements in checker assemblies.

More particularly the present invention relates to an assembly of checkerbricks such as used in blast furnace stoves or other heat exchange media.

An object of the present invention is to provide a checker assembly involving checkers of conventional design but disposed in such relationship with one another that efficient interlocking is provided and the danger of shifting is minimized.

A further object is to provide an improved arrangement of checkers providing continuous channels from top to bottom of the arrangement, which arrangement affords efficient interlocking and avoids continuous joint planes along which checkers can shift.

Further objects will appear as the description proceeds.

Referring to the drawings—

Figure 1 is a fragmentary plan view of an arrangement of checkers embodying the principles of the present invention; and

Figure 2 is a sectional view taken along the plane indicated by the arrows 2—2 of Figure 1.

The arrangement of checkers according to the present invention embodies a plurality of checkers indicated by the letters H—H and L—L. Said checkers may be identical in contour and each may be an elongated rectangular parallelopiped. Each of the checkers is provided with a plurality of holes M—M, each checker in the illustrated embodiment of the invention having three holes symmetrically disposed with respect to the corresponding checker. The three holes in each checker have their axes in co-planar relationship.

As shown in Figure 1, the checkers H—H are disposed in herringbone arrangement with the checkers L—L. Expressed in other language, the checkers H—H are arranged in echelon with respect to one another in parallel files and the checkers L—L are arranged in echelon with respect to one another in parallel files, the long dimensions of the checkers H—H being at right angles to the long dimensions of the checkers L—L. As viewed in plan, a short dimension of each checker H is in abutting relationship with the long dimension of a checker L. Likewise, a short dimension of a checker L as viewed in plan is in abutting relationship with the long dimension of a checker H. As illustrated in the drawing, the hole M in each end portion of each checker abutted by a short end surface of a neighboring checker has its axis in co-planar re-

2

lationship with the axes of the holes in said neighboring checker.

As shown in Figure 2, the checkers L—L are disposed at different levels from the checkers H—H, breaking joint with said checkers H—H, thereby avoiding continuous horizontal joint planes along which the checkers can shift. Otherwise expressed, the checkers L—L in one layer are displaced vertically from the checkers H—H in the next adjacent layer a distance less than the height of a checker L or H. As shown in Figure 2, the checkers L—L are shown symmetrically disposed with respect to the planes which mark the contacts between adjacent layers of the checkers H—H.

It will be noted that the holes M—M are in alignment from top to bottom of the checker arrangement, thereby providing continuous flues for the passage of gas or air.

20 Though a preferred embodiment of the present invention has been described in detail, many modifications will occur to those skilled in the art. It is intended to cover all such modifications that fall within the scope of the appended claims.

25 What is claimed is:

1. In combination, a plurality of checkers of similar contour, each comprising a rectangular parallelopiped, said checkers being arranged in a plurality of layers, the checkers in one of said layers being displaced vertically from the checkers in the other layers a distance less than the height of a checker, each of said checkers having an elongated rectangular cross-sectional contour in a plane parallel with said layer and being provided with a plurality of holes disposed transversely of said layers, the holes in each of said checkers having their axes in co-planar relationship with each other and in registry with the holes in checkers in adjacent layers.

2. In combination, a plurality of checkers of similar contour, each comprising a rectangular parallelopiped, said checkers being arranged in a plurality of layers, the checkers in one of said layers being displaced vertically from the checkers in the other layers a distance approximately equal to half the height of a checker, each of said checkers having an elongated rectangular cross-sectional contour in a plane parallel with said layer and being provided with a plurality of holes disposed transversely of said layers, the holes in each of said checkers having their axes in co-planar relationship with each other and in registry with the holes in checkers in adjacent layers.

3. In combination, a plurality of checkers of similar contour, each comprising a rectangular parallelopiped, said checkers being arranged in

two groups, the checkers in one of said groups being arranged in parallel files, the checkers in each of said files being arranged in echelon with respect to each other, the checkers in the other of said groups being also arranged in parallel files, the checkers thereof being arranged in echelon with each other, the end surfaces of the checkers in each of said groups abutting the sides of the checkers in the other of said groups each of said checkers having an elongated rectangular cross-sectional contour in a plane parallel with said layers and being provided with a plurality of holes disposed transversely thereof, the end holes of each checker abutted by an end surface of a neighboring checker, having their axes in co-planar relationship with the axes of the holes in said neighboring checker, said checkers being arranged in layers, the holes in the checkers in each layer being in registry with the holes in the checkers in adjacent layers.

4. In combination, a plurality of checkers of similar contour, each comprising a rectangular parallelopiped, said checkers being arranged in two groups, the checkers in one of said groups being arranged in parallel files, the checkers in each of said files being arranged in echelon with respect to each other, the checkers in the other of said groups being also arranged in parallel files, the checkers thereof being arranged in echelon with each other, the end surfaces of the checkers in each of said groups abutting the sides of the checkers in the other of said groups, the checkers in said groups being displaced vertically from the checkers in the other of said groups a distance less than the height of a checker each of said checkers having an elongated rectangular cross-sectional contour in a plane parallel with said layers and being provided with a plurality of holes disposed transversely thereof, the end holes of each checker abutted by an end surface of a neighboring checker, having their axes in co-planar relationship with the axes of the holes in said neighboring checker, said checkers being arranged in layers, the holes in the checkers in each layer being in registry with the holes in the checkers in adjacent layers.

5. In combination, a plurality of checkers of similar contour, each comprising a rectangular parallelopiped, said checkers being arranged in two groups, the checkers in one of said groups being arranged in parallel files, the checkers in each of said files being arranged in echelon with respect to each other, the checkers in the other of said groups being also arranged in parallel files, the checkers thereof being arranged in echelon with each other, the end surfaces of the checkers in each of said groups abutting the sides of the checkers in the other of said groups, the checkers in one of said groups being displaced vertically from the checkers in the other of said groups a distance approximately equal to half the height of a checker each of said checkers having an elongated rectangular cross-sectional contour in a plane parallel with said layers and being provided with a plurality of holes disposed transversely thereof, the end holes of each checker abutted by an end surface of a neighboring checker, having their axes in co-planar relationship with the axes of the holes in said neighboring checker, said checkers being arranged in layers, the holes in the checkers in each layer being in registry with the holes in the checkers in adjacent layers.

6. In combination, a plurality of checkers of similar contour, each comprising a rectangular

parallelopiped, the checkers in one of said groups being arranged in parallel files, the individual checkers being arranged in echelon, the checkers in the other of said groups being arranged in parallel files, the individual checkers thereof being arranged in echelon, the checkers in one of said groups being disposed in herringbone arrangement with the checkers in the other of said groups each of said checkers being provided with a plurality of holes disposed transversely thereof, the end holes of each checker abutted by an end surface of a neighboring checker, having their axes in co-planar relationship with the axes of the holes in said neighboring checker, said checkers being arranged in layers, the holes in the checkers in each layer being in registry with the holes in the checkers in adjacent layers.

7. In combination, a plurality of checkers of similar contour, each comprising a rectangular parallelopiped, the checkers in one of said groups being arranged in parallel files, the individual checkers being arranged in echelon, the checkers in the other of said groups being arranged in parallel files, the individual checkers thereof being arranged in echelon, the checkers in one of said groups being disposed in herringbone arrangement with the checkers in the other of said groups, the checkers in said groups being displaced vertically a distance less than the height of a checker each of said checkers being provided with a plurality of holes disposed transversely thereof, the end holes of each checker abutted by an end surface of a neighboring checker, having their axes in co-planar relationship with the axes of the holes in said neighboring checker, said checkers being arranged in layers, the holes in the checkers in each layer being in registry with the holes in the checkers in adjacent layers.

8. In combination, a plurality of checkers of similar contour, each comprising a rectangular parallelopiped, the checkers in one of said groups being arranged in parallel files, the individual checkers being arranged in echelon, the checkers in the other of said groups being arranged in parallel files, the individual checkers thereof being arranged in echelon, the checkers in one of said groups being disposed in herringbone arrangement with the checkers in the other of said groups, the checkers in said groups being displaced vertically a distance approximately equal to half the height of a checker each of said checkers being provided with a plurality of holes disposed transversely thereof, the end holes of each checker abutted by an end surface of a neighboring checker, having their axes in co-planar relationship with the axes of the holes in said neighboring checker, said checkers being arranged in layers, the holes in the checkers in each layer being in registry with the holes in the checkers in adjacent layers.
